CLAIM

The ornamental design for a computer housing or similar article, as shown and described.

DESCRIPTION

FIG. 1 is a top front and right side perspective view of a computer housing or similar article showing our new design;

FIG. 2 is a front elevational view thereof on an enlarged scale;

FIG. 3 is a rear elevational view thereof on an enlarged scale;

FIG. 4 is a left side elevational view thereof on an enlarged scale;

FIG. 5 is a right side elevational view thereof on an enlarged scale;

FIG. 6 is a top plan view thereof on an enlarged scale; and,

FIG. 7 is a bottom plan view thereof on an enlarged scale.
